UNITED STATES PATENT OFFICE.

RICHARD TRÖGER, OF CHARLOTTENBURG, GERMANY, ASSIGNEE TO GENERAL ELECTRIC COMPANY, A CORPORATION OF NEW YORK.

GOVERNING MECHANISM FOR CENTRIFUGAL COMPRESSORS.

1,076,332.

Specification of Letters Patent.

Patented Oct. 21, 1913.

Application filed December 28, 1911. Serial No. 668,340.

To all whom it may concern:

Be it known that I, RICHARD TRÖGER, a subject of the King of Prussia, residing at Charlottenburg, Germany, have invented 5 certain new and useful Improvements in Governing Mechanism for Centrifugal Compressors, of which the following is a specification.

Certain types of centrifugal compressors, 10 with which I am familiar, have been provided with a relief or blow-off valve located in the discharge pipe that is intended to open when the work performed by the compressor falls below a certain predetermined 15 small value. The object of the valve is to prevent surging or pumping, as it is commonly designated, of the fluid undergoing compression. These blow-off valves have been actuated either by means of a non-re- 20 turn valve located in the discharge pipe, or by a means which is responsive to a pressure difference existing between two points in the discharge pipe, which pressure difference bears a definite relation to the work 25 performed by the compressor. These devices are open to certain material disadvantages, which it is the purpose of my present invention to overcome. In the first place the power available for operating the 30 blow-off valve is comparatively small and depends to a certain degree upon atmospheric conditions. In the second place, the friction of the moving parts of the blow-off valve and of its actuating means has to be 35 taken into account; this being a more or less uncertain quantity which increases with the life of the apparatus by reason of impurities of one kind or another that are deposited on the parts. Due to lack of power 40 or to friction or both the valve may even fail to operate. These various objections have resulted in practice in adjusting the blow-off valve so that it opens before the work performed by the compressor has been 45 reduced to the lowest permissible value. That is to say, the parts are so set that the blow-off valve instead of opening just as the surging is about to take place opens while the load is considerably above that 50 value. In other words, with the arrangements heretofore used, the effective range of the compressor has been unduly reduced. Furthermore, owing to the unfavorable conditions existing between the actuating means 55 and the blow-off valve, the latter is caused

to open spasmodically, thus giving rise to impulses or pulsations in the compressor, and also in the net work of tubular passages connected thereto.

I avoid the difficulties above mentioned 60 first, by so arranging the blow-off valve that it is dependent as to its position upon the work performed by the compressor and hence of the motor that drives it, and second, by positively actuating said valve. By 65 reason of my improved construction or arrangement, the blow-off valve will not be opened until the work performed by the compressor has been decreased to its smallest permissible value, and in this manner 70 the effective range of the compressor is increased.

In the accompanying drawing which illustrates one of the embodiments of my invention, Figure 1 shows a centrifugal air 75 compressor driven by an electric motor, and Fig. 2 is a modification wherein the blow-off valve of the discharge pipe is connected to a throttle valve in the inlet pipe.

1 is a rotary compressor of any suitable 80 construction having an admission conduit 2 and a discharge conduit 3. Located in the discharge conduit is a blow-off valve 4, which is actuated by means of a two-part 85 stem or rod 5, the upper end of the rod being connected to the valve, and the lower end to a projection on the worm gear segment 6. By dividing the valve actuator into two parts as shown, a lost motion connection is provided which permits the gear 90 to move through a portion of its range without disturbing the valve. The compressor is driven by an electric motor 7 of any suitable construction. As shown, it is driven by a shunt wound direct current machine. 95

8 and 9 indicate the mains supplying current to the motor. In circuit with the field winding 10 of the motor is a resistance 11 of suitable construction. Arranged to travel over the contact points connected to the resistance is an arm 12 that has attached to it a worm gear segment 13. Located between the worm gear segments 6 and 13 is a worm 14, the latter being rotated in one direction or the other to change the resistance in the field circuit by the hand wheel 15. As the load on the compressor increases, the resistance is adjusted so that the speed of the motor will increase. Conversely, as the load on the compressor decreases, the re- 100 105 110

sistance is adjusted to decrease the speed of the motor. Owing to the fact that the worm 14 meshes with the segments 6 and 13, it follows that any movement of one causes 5 a movement of the other. Under normal conditions, the blow-off valve 4 rests on its seat, and the lower part of the stem 5 moves up and down without affecting it. When, however, the segment 6 is swung to the 10 right, the lost motion between the parts of the valve stem is first taken up and then the blow-off valve is opened permitting compressed air or other fluid to escape from the discharge pipe 3. The opening of the 15 valve 4 takes place only when the motor is operating at nearly its lowest speed. When it is operating at higher speeds, the lower part of the valve stem 5 moves away from the upper part and the pressure in the 20 pipe 3 holds the valve against its seat.

In Fig. 2 the valve 4 is arranged as before and is actuated by a bell-crank lever 16, which in turn is operated by a crank 17 on the lower end of the stem 18 of a butterfly 25 throttle valve 19. The upper end of its stem is provided with a pinion 20 that meshes with a gear 21, the latter being actuated by a pinion 22 that is on the shaft 23. When the butterfly valve is moved to a position, 30 where it nearly closes the inlet 2, the bell-crank lever 16 will begin to open the blow-off valve. This opening of the blow-off valve increases as the throttling effect in the inlet pipe, due to the butterfly valve, is 35 increased. Conversely, when the butterfly valve is opened it permits the blow-off valve 4 to seat and thereafter has no effect. To state the matter in another way, a throttling valve is provided in the inlet and a 40 blow-off valve in the outlet, which valves are connected through a lost motion connection that is so arranged that the valves may operate simultaneously under certain conditions, and separately under other 45 conditions.

I have described and illustrated two forms of lost motion connections or devices between the stem of the blow-off valve and its actuator, but it is to be understood that 50 any other device suitable for the purpose may be provided.

It will be evident from the description and illustration that the blow-off valve can be accurately adjusted to open just before 55 the load has been reduced (either by cutting off consumption devices or other means), to that certain predetermined value where surging can take place. This means that the effective range of the apparatus 60 has been increased because the opening of the blow-off valve has been delayed to the last moment, and because the definite opening of the valve at the proper time has been assured.

65 Since the work performed by the com-

pressor varies with that of the motor, and since there is a direct relation between the position of the regulator of the motor and that of the blow-off valve, it follows that the latter is responsive to the amount of work performed by the compressor. In one aspect of my invention the driving motor and its regulator constitute a means for varying the output of the compressor, and since the position of the blow-off valve is determined directly by the regulator and indirectly by the speed of the motor it follows that said means control the blow-off valve. Of course, without going outside the invention, the performance-regulating members of the compressor upon which the blow-off valve is dependent, may be adjusted automatically in any way instead of by hand as shown. Automatic and hand operated members for controlling the work performance 80 of the compressor may be used in the same machine, in which case the blow-off valve should be so arranged as to be under the control of both of said members.

The electric motor shown may be taken 90 as typical of any form of motor, and the regulator as typical of any form of regulator suitable for the motor with which it is associated.

In accordance with the provisions of the 95 patent statutes, I have described the principle of operation of my invention, together with the apparatus which I now consider to represent the best embodiment thereof; but I desire to have it understood that the 100 apparatus shown is only illustrative, and that the invention can be carried out by other means.

What I claim as new and desire to secure by Letters Patent of the United States, is— 105

1. In combination, a centrifugal compressor which is subject to surging at light loads, a means for varying the output of the compressor, and a valve for regulating the amount of fluid delivered by the compressor which is actuated by the said means. 110

2. In combination, a centrifugal compressor which is subject to surging at light loads, a means for varying the output of the compressor, and a surge preventing valve that is 115 located on the discharge side of the compressor and is opened responsive to said means when the output is reduced to such a small percentage of the total that surging would otherwise take place. 120

3. In combination, a centrifugal compressor which is subject to surging at light loads, a means for regulating the amount of work performed by the compressor, a normally closed valve which when opened prevents the 125 load on the compressor from falling below a predetermined amount, and a lost motion connection between said means and the valve which is arranged to move the valve when the regulating means has decreased the out- 130

- put of the compressor to a point where surging would otherwise take place.
4. In combination, a centrifugal compressor which is subject to surging at light loads, 5 inlet and discharge conduits therefor, a driving motor, a regulator for the motor, a normally closed valve in one of the conduits that is adapted to be opened to prevent the load on the compressor from falling below the point where surging takes place, and means that is common to the regulator and valve for moving the regulator and opening the valve against the pressure in its conduit.
- 10 5. In combination, a centrifugal compressor which is subject to surging at light loads, 15 inlet and discharge conduits therefor, a driving motor, a regulator for the motor, a valve in one of the conduits that is adapted to be opened to prevent the load on the compressor from falling below a predetermined minimum, a means common to the regulator and valve for actuating them, and a lost motion connection between the means and the valve.
- 20 6. In combination, a centrifugal compressor which is subject to surging at light loads, 25 inlet and discharge conduits therefor, a driving motor, regulating mechanism for the motor, a blow-off valve which when open prevents the load on the compressor from falling below a predetermined amount, and a connection between the regulating mecha-
- nism and the valve which opens the latter when the amount of energy admitted to the motor by the regulator has been reduced to 35 a predetermined value.
7. In combination, a centrifugal compressor which is subject to surging at light loads, 40 inlet and discharge conduits therefor, a blow-off valve in the discharge conduit which when open prevents the load on the compressor from falling below a predetermined amount, a driving motor, a regulator for the motor, an actuator for the regulator, a means moved by the actuator, and a 45 stem for the valve that is actuated by said means through a lost motion connection.
8. In combination, a centrifugal compressor having inlet and discharge conduits, a 50 valve in one of the conduits, a motor for driving the compressor, a regulator for the motor, means for actuating the valve, means for actuating the regulator, a device which is situated between the said valve and regulator means for actuating both of them, and 55 a lost motion connection included in one of the means.

In witness whereof, I have hereunto set my hand this 26th day of December, 1911.

RICHARD TRÖGER.
